UNITED STATES PATENT OFFICE

WALLACE S. WARNOCK, OF CHICAGO, ILLINOIS

PRINTER'S REGISTER HOOK

Application filed June 14, 1929. Serial No. 371,034.

My invention relates to printers' register hooks that are insertable within grooves formed in beds or foundations and are provided with gearing that coacts with gearing 5 in the grooves whereby bodily travel of the register hooks may be effected. The invention has for its object the provision of improved means whereby the gearing may be locked to prevent the register hooks from 10 advancing or receding. In accordance with my invention a detent is provided which presses upon an operating gear that is carried by the body of the register hook. This gear that is thus engaged by the detent is 15 preferably one which is accessible for operation through the hook and which is operable by a suitable tool that is adapted for turning engagement with this gear. The detent is preferably of U form being anchored, 20 at one end, upon the body of the register hook and projecting, at its other end, through a slot in the body of the register hook to have engagement with the operating gear that is actuated by a tool passed 25 through the register hook jaw. The walls of the slot guard the gear engaging end of the detent and serve to hold the detent from material rotary movement when the detent is provided with a single anchorage which is 30 preferably a shaft or bolt upon which a second gear is mounted to be turned by the first gear that is preferably in mesh therewith. This bolt or shaft desirably also constitutes a means for assembling the retaining device 35 by which the register hook is assembled with the bed in a manner to permit the register hook to move along the groove that receives it, but to prevent the hook from being lifted. 40 I will explain my invention more fully by reference to the accompanying drawing in which Fig. 1 is a view showing the register hook of my invention in elevation and a portion of a bed, that receives the body of the 45 register hook, in section; Fig. 2 is a sectional view on line 2-2 of Fig. 1; Fig. 3 is a sectional view on line 3-3 of Fig. 1; Fig. 4 is a sectional view on line 4-4 of Fig. 2; Fig. 5 is a perspective view illustrating some of 50 the parts of the register hook and also the

detent which is illustrated in unassembled relation; Fig. 6 is a sectional view on line 6-6 of Fig. 4; and Fig. 7 is a sectional view, on a larger scale, on line 7-7 of Fig. 4.

The register hook illustrated is inclusive of a body portion 1 in the form of an inverted U and a jaw 2 having a stem 3 which is journaled within the upper portion of the body 1. A circular washer 4 is received within registering grooves that are provided in the stem 3 and body 1, whereby the jaw 2 is confined to a fixed plane of rotation with respect to the register hook body. The body 1 of the register hook is sufficiently narrow to be receivable within any selected groove 5 provided in the printing bed or foundation 5'. This groove is formed with lateral enlargements 6 to afford retaining shoulders 7. Any suitable form of retaining device 60 may be carried by the register hook. The retaining device illustrated is inclusive of two side bars 8 which are joined near their ends by U-shaped spring members 9. These bars are received within grooves 10 which are formed longitudinally in the register hook body 1 and in the sides of this body. These grooves are sufficiently deep to permit the bars to be fully received therein, when such bars are abreast of the register hook body, to permit the register hook body 65 to be dropped into the selected groove 5 and into a position in which the bars are in register with the enlargements 6 of the groove 5. The ends of the bars slope toward each other, as illustrated most clearly in Fig. 3, to enable a suitable form of tweezer to be applied thereto, such tweezer having camming engagement with the ends of the bars, whereby the bars may be contracted 70 against the force of the springs 9 in order 75 that the register hook body may be dropped into the selected groove 5 or to enable such body to be withdrawn from such groove, as desired. 80

A bolt or shaft 11 is disposed lengthwise of the register hook body 1 and near the bottom thereof. This bolt or shaft is screwed into the sleeve bolt 12, the register hook body being clamped between the heads of both bolts. The gearing which is employed to 85

90

95

100

effect the longitudinal travel of the register hook body along the groove 5 in either direction is inclusive of an upright beveled gear 13 which is coaxial with the jaw stem 3, a horizontal beveled gear 14 which is journaled upon and is coaxial with the bolt or shaft 11, a worm screw 15 which is preferably integrally formed with the gear 14 and is rotatable upon the shaft 11 and the 10 stationary racks 16 which are provided in the bottom of the groove 5. The stem 3 of the jaw 2 is provided with a cylindrical bore that is coaxial with the beveled gear 13. This beveled gear is formed with a square 15 bore which is adapted to receive the square shank of a wrench which is applied whenever the register hook is to be moved along the groove 5. When this wrench is turned the beveled gear 13 is turned, this gear turning the beveled gear 14 meshing therewith, the worm 15 turning with the gear 14 to force the movement of the register hook body 1 along the groove 5.

In order that the gearing 13, 14 and 15 25 may be held in the position to which it is adjusted, I employ a spring detent 17 which is preferably of U form. This detent is formed with an eye 18 at one end, the shaft or bolt 11 being passed through this eye. 30 The eye end of the detent is next to the head of the bolt 11 and is clamped or retained between this bolt head and the adjacent side of the body 1. The free or unmounted end 35 of the detent 17 projects through a slot 19 that is formed in the end of the register hook body 1 where the gear 13 is disposed. This slot exposes the adjacent side of the gear 13, the walls of the slot guarding the free or un- 40 mounted end of the detent and the side slot walls serving to prevent material turning movement of the detent on the shaft or bolt 11.

The nose of the detent is rounded and is 45 sufficiently broad to be engageable, at the same time, with the adjacent surfaces of any two adjacent teeth of the gear 13. When the gear 13 is stopped at a place to permit the nose of the detent to enter between any 50 two adjacent teeth, the detent nose serves to hold such gear from turning movement in either direction. If the gear 13 should be stopped with the crown of one of its teeth opposite the nose of the detent, the detent 55 serves to hold the gear in this position, the detent and the crowns of the teeth being formed with interengaging holding formations. These interengaging formations are desirably the rounded end of the nose and 60 the concave faces 20 which are formed in the crowns of the teeth and extend lengthwise of the axis of the gear. The gear ratios are such that the movement of the register hook body 1 along the groove 5 is minute in relation to the distances between the teeth and 65

between the crowns of the teeth and the adjacent interteeth spaces.

Changes may be made without departing from the invention.

Having thus described my invention, I 70 claim:

1. In a printer's register hook, the combination with the body portion thereof; of a jaw at the top side of the said body portion; a beveled gear journaled within the body 75 portion, this gear having a bore formed to afford turning engagement of a wrench therewith and said jaw having an opening in alignment with said bore to afford passage for the wrench; a second beveled gear in 80 mesh with the aforesaid beveled gear; a shaft for said second beveled gear, this shaft being carried by the aforesaid body portion; a gear driven by the second beveled gear and provided for engagement with a stationary rack; and a detent in the form of a spring, the shaft passing through one end of the 85 spring and having a head in retaining engagement with this spring end, the unmounted end of the spring passing through a 90 slot that is provided in the aforesaid body portion in the region of the first aforesaid beveled gear and through which slot the aforesaid detent passes into engagement with this gear, the engaging end of the spring being receivable between adjacent teeth to have engagement therewith, the crowns of the teeth of this gear being formed with concave faces which also are adapted to receive the engaging end of the detent. 100

2. In a printer's register hook, the combination with the body portion thereof; of a jaw at the top side of the said body portion; a beveled gear journaled within the body portion, this gear having a bore formed to afford turning engagement of a wrench therewith and said jaw having an opening in alignment with said bore to afford passage for the wrench; a second beveled gear in mesh with the aforesaid beveled gear; a shaft for said second beveled gear, this shaft being carried by the aforesaid body portion; a gear driven by the second beveled gear and provided for engagement with a stationary rack; and a detent in the form of a spring, the shaft passing through one end of the spring and having a head in retaining engagement with this spring end, the unmounted end of the spring passing through a slot that is provided in the aforesaid body portion in the region of the first aforesaid beveled gear and through which slot the aforesaid detent passes into engagement with this gear, the engaging end of the spring being receivable between adjacent teeth to have engagement therewith. 115

3. In a printer's register hook, the combination with the body portion thereof; of 120

a jaw at the top side of the said body portion; a beveled gear journaled within the body portion, this gear having a bore formed to afford turning engagement of a wrench therewith and said jaw having an opening in alignment with said bore to afford passage for the wrench; a second beveled gear in mesh with the aforesaid beveled gear; a shaft for said second beveled gear, this shaft being carried by the aforesaid body portion; a gear driven by the second beveled gear and provided for engagement with a stationary rack; and a 10 detent in the form of a spring, the shaft passing through one end of the spring, and having a head in retaining engagement with this spring end, the unmounted end of the spring passing through a slot that is provided in the aforesaid body portion in the 15 region of the first aforesaid beveled gear and through which slot the aforesaid detent passes into engagement with this gear, the crowns of the teeth of this gear being formed with concave faces which are adapted to 20 receive the engaging end of the detent.

4. In a printer's register hook, the combination with the body portion thereof; of a jaw at the top side of the said body portion; a beveled gear journaled within the body portion, this gear having a bore formed to afford turning engagement of a wrench therewith and said jaw having an opening in alignment with said bore to afford passage for the wrench; a second beveled gear in mesh with the aforesaid beveled gear; a shaft for said second beveled gear, this shaft being carried by the aforesaid body portion; a gear driven by the second beveled gear and provided for engagement 30 with a stationary rack; and a detent in the form of a spring, the shaft passing through one end of the spring and having a head in retaining engagement with this spring end, the unmounted end of the spring passing through a slot that is provided in the aforesaid body portion in the region of the first aforesaid beveled gear and through which slot the aforesaid detent passes into engagement with this gear, the detent and gear being formed with interengaging formations enabling the detent to hold this gear in the position to which it is turned.

In witness whereof, I hereunto subscribe my name.

55 WALLACE S. WARNOCK.
